UNITED STATES PATENT OFFICE.

ALBERT C. LOTTMAN, OF HOUSTON, TEXAS.

MOSQUITO-NET FRAME.

SPECIFICATION forming part of Letters Patent No. 367,151, dated July 26, 1887.

Application filed February 23, 1887. Serial No. 228,556. (No model.)

To all whom it may concern:

Be it known that I, ALBERT C. LOTTMAN, of Houston, in the county of Harris and State of Texas, have invented a new and Improved 5 Mosquito-Net Frame, of which the following is a full, clear, and exact description.

My invention relates to a mosquito - net frame, and has for its object to provide a frame which may be frequently taken apart and 10 joined again without the slightest damage to the connections, and wherein the said frame will be effective, durable, and ornamental.

The invention consists in the construction and combination of the several parts, as will 15 be hereinafter fully set forth, and pointed out in the claims.

Reference is to be had to the accompanying drawings, forming a part of this specification, in which similar letters of reference indicate 20 corresponding parts in all the figures.

Figure 1 is a perspective view of my frame attached to a bed; Fig. 2, an enlarged detail perspective view thereof, and Fig. 3 an enlarged horizontal section through the stand- 25 ard-head.

In carrying the invention into effect two standards, A. A', are employed, having attached to their upper ends a rounded head, B. The said standards are united by a horizontal 30 bar, a, having reduced ends adapted to enter aligning apertures b in opposing sides of the standard-heads B, a rigid attachment of the bar a to said heads being effected by the passage of detachable pins C through the heads, 35 and also through the reduced ends of the bar a, an aperture, c, being made in the heads and a registering-aperture through the reduced ends of the rod to accommodate the said pins.

Duplicate apertures b and c are made in 40 the front side of the standard-heads B, and horizontal side bars, D, are held in said apertures at one end by the detachable pins C in a similar manner to the attachment of the rear horizontal bar, a.

The upper portion of the frame is completed by the attachment to the outer ends of 45 the side bars, D, of detachable ornamental heads E, which are preferably of the same size and design as the aforesaid standard-heads B,

and also the attachment to said detachable 50 heads of a front horizontal bar, D', the attachment of both the side bars and front bar being effected by detachable pins entered diagonally through the heads, the reduced ends of the said bars receiving said pins being entered 55 aligning apertures in said heads. It will be thus seen that the upper extended portion of the frame is rectangular in form, consisting of front, side, and rear bars adjustably united by a series of detachable pins to ornamental heads 60 located at each corner.

The upper extended portion of the frame is supported by brackets F, detachably attached to the standards A. A' and to the under side of the horizontal side bars, D, the attachment 65 being made by the lower inner edge of said brackets engaging an upwardly-inclined pin, f, secured in the standards, and the entrance of a pin, f', secured to the top of said bracket in the under side of said side bars, and inclined upwardly in an opposite direction to that of the pin f to enter a similarly inclined hole.

The canopy-frame is secured to the bed by a downwardly-inclined pin, H, secured about 75 the center of the standards, adapted to be entered in a diagonal aperture at the top or rear side near the ends of the bedstead, the frame being further stayed by the angular bar h, pivoted in the lower ends of the standards, 80 adapted to be passed under the edge of the head-board or bed-frame at the back.

It will be observed that the frame may be readily detached and folded in a small compass, and that when in position a rigid ornamental structure is obtained.

Having thus fully described my invention, what I claim as new, and desire to secure by Letters Patent, is—

1. In a mosquito-net frame, the combination, with the standards A. A', provided with detachable heads B, of the rear horizontal bar, a, horizontal side bars, D, front horizontal bar, D', and a detachable bracket, F, and upwardly-inclined pins f, f', secured, respectively, 90 to the standard and to the bracket in similarly-inclined holes, substantially as shown and described.

2. In a mosquito-net frame, the combination of a mosquito-net frame, with the standards A A', provided with detachable heads B, horizontal bars *a*, D, and D', a detachable bracket, F, and downwardly-inclined pins H, secured to the standards A A', adapted to enter a diagonal aperture at the upper ends of the bedstead, and an angu-

lar bar, h, pivoted to the lower ends of the standards to be passed under the edge of the head-board, substantially as described.

ALBERT C. LOTTMAN.
